UNITED STATES PATENT OFFICE.

OSCAR V. PAYNE, OF CLEVELAND, OHIO, ASSIGNOR TO AUTO-ORDNANCE CORPORATION, OF NEW YORK, N. Y., A CORPORATION OF NEW YORK.

GUN.

1,397,698.

Specification of Letters Patent. Patented Nov. 22, 1921.

Application filed December 20, 1919. Serial No. 346,406.

To all whom it may concern:

Be it known that I, OSCAR V. PAYNE, a citizen of the United States, and resident of Cleveland, in the county of Cuyahoga and 5 State of Ohio, have invented new and useful Improvements in Guns, of which the following is a specification.

This invention relates to automatic guns of the type disclosed in the Patent to Blish 10 1,131,319, granted March 9, 1915, and in applications Serial No. 203,873, filed November 26, 1917, Serial No. 203,887, filed November 26, 1917, Serial No. 282,642, filed March 14, 1919, and Serial No. 308,223, filed July 2, 15 1919, viz., of the type having a breech lock provided with oblique locking surfaces so inclined to the line of breech pressure that the breech is held in closed position during high breech pressure but is automatically 20 unlocked directly by the breech pressure after the pressure has decreased to a relatively low value.

The object of the invention is to improve the construction and disposition of the breech 25 lock in guns of the aforesaid type with a view to increase the strength and durability of the lock and associated parts, to insure uniform and unfailing action of the breech closure, to increase the effective bearing surfaces 30 of the lock without substantially increasing the over-all dimensions of the parts, to reduce or eliminate the shearing stresses on the lock, to simplify the construction and reduce the cost of manufacture of guns of 35 this type, and generally to improve the action of such guns.

For the purpose of illustrating my invention I have shown one concrete embodiment in the accompanying drawings, in which— 40 Figure 1 is a vertical axial section, showing parts broken away and other parts in elevation;

Fig. 2 is a top plan;

Fig. 3 is a transverse section on line 3—3 45 of Fig. 1;

Fig. 4 is a left side elevation of the breech unit, comprising the bolt, firing member and lock, removed from the gun;

Fig. 5 is a top plan of the same unit;

50 Fig. 6 is a front elevation of the lock;

Fig. 7 is a rear elevation of the lock;

Fig. 8 is a section on line 8—8 of Fig. 6; and

Fig. 9 is a section on line 9—9 of Fig. 6.

55 The particular embodiment of the inven-

tion chosen for the purpose of illustration comprises a hand machine gun having a receiver R, a barrel A threaded into the forward end of the receiver, a cooling tube T around the barrel, a frame F slidably interlocked over the open bottom of the receiver, a shoulder piece K and a hand grip G mounted on the frame F, a magazine M detachably secured beneath the receiver by a catch C, a bolt B slidable in the receiver, a lock L interposed between shoulders or abutments on the bolt and receiver respectively, a firing member comprising two parts M and N hooked together, a recoil spring S, a buffer U, and a sight H. The trigger mechanism 60 carried by the frame F forms the subject matter of application Serial No. 297,282, filed May 15, 1919, and the magazine M is claimed in application Serial No. 297,286, 65 filed May 15, 1919.

The bolt is recessed on top to receive the firing member M and the recoil spring S as shown in Figs. 1, 3 and 5, the recess being wide throughout the rearward end of the bolt to receive the spring, and relatively narrow throughout the forward end to accommodate the firing member which is substantially flat throughout its entire length. The firing pin N is disposed in an axial opening 70 in the forward end of the bolt and hooks under a shoulder on the member M at its rearward end. The rearward end of firing member M projects into the spring recess and the recoil spring abuts against the end of the firing member and not against the bolt, the 75 pressure of the spring being transmitted to the bolt through the medium of the firing member and lock as hereinafter described. An actuator 4 projects upwardly from the forward end of the member M through a 80 slot 5 in the receiver to provide means for manually retracting the breech closure when desired. The member M is provided with a transverse slot 1 on its upper side to receive a portion of the lock as hereinafter 85 described, the slot sloping forwardly from top to bottom.

The bolt B is provided on its opposite sides with oblique grooves 2 which extend from the top to the bottom of the bolt and 90 which incline rearwardly from top to bottom. The grooves 2 are at least as deep as the side walls of the bolt so that the grooves extend entirely through the side walls, in the form of slots, above the level of the bottom 95 100 105 110

- 3 of the recess for the recoil spring. As shown in Figs. 2 and 5 the bolt is somewhat wider in the rear of the grooves 2 than in front thereof.
- 5 The lock L comprises two legs 6 slidably fitting in the grooves 2 respectively on the opposite sides of the bolt and a body portion joining the legs together at their upper ends. The legs 6 are provided at their outer 10 forward corners with tapering recesses 8 which form shoulders 9 sloping rearwardly from top to bottom at an angle to the vertical greater than the angle of the lugs 6. The outer faces of the lugs 6 are flush with 15 the sides of the wider portion of the bolt in the rear of the grooves 2 and the lateral faces of the recessed portions 8 are flush with the sides of the narrower portion of the bolt immediately in front of the grooves 2.
- 20 The body 7 of the lock is provided with a bearing surface 10 parallel (or diverging somewhat from top to bottom) with respect to the shoulders 9, this bearing surface extending uninterruptedly throughout the full 25 width of the lock. The lock also has transverse faces 11, 12, 13, and 14, face 11 being horizontal, face 12 being approximately perpendicular to face 10, face 13 sloping forwardly from top to bottom, face 14 being flush with the forward faces of legs 6, and face 15 being substantially perpendicular to the plane of the bisector of the angle between faces 10 and 14. The lock body 7 is provided with a central slot 16 on its 30 front and bottom to receive the firing member M and with a central shoulder 17 on the rear to bear against the rear face of slot 1 in the firing member, the slot 16 and shoulder 17 shaping the central portion of 35 40 the lock body to fit slidably in the slot in the firing member as shown in Fig. 1.
- The receiver R is provided with a transverse arched portion 18 to receive the upper portion of the lock, this arched portion being 45 provided with a bearing plate 19, of bronze-steel or other hard bearing material, against which the lock surface 10 is adapted to abut, and with a surface 20 against which the lock surface 12 is adapted to abut. The bearing 50 plate 19 is dovetailed into the receiver at 21 and a pin 22, adapted to be inserted through an opening at one side of the receiver, is provided to retain the plate in position. A lubricant duct 23 may lead inwardly from 55 the side of the receiver and thence downwardly and forwardly through the plate 19 to the bearing surfaces between the lock and plate. The receiver is widened at 24 and 25 (Fig. 2) in the region of the lock 60 to increase its strength. In the rear of the line 27 (Fig. 1) the receiver chamber is slightly wider than the widest portions of the bolt and lock to receive these portions with a free sliding fit. In front of the line 65 27 (Fig. 1) the receiver chamber is less wide by an amount equal to the depths of the recesses 8 in the lock, thereby forming shoulders 28 and 29 (Fig. 2) in the plane of line 27 against which the shoulders 9 on the lock are adapted to abut. The body of the bolt extends rearwardly to the plane of line 30 (Fig. 1), that is to the plane of the forward ends of the spring recess and the grooves 2, thereby having a bearing face in this place adapted to abut against the face 14 of the lock throughout its entire width except at the central slot provided for firing member M.
- The operation of the breech closure is as follows: when the gun is fired the breech pressure is transmitted through the bolt to the lock throughout the bearing surface 14 of the lock and thence to the receiver throughout the surface 10 of the lock which bears against the bearing plate 19. The lock-receiver bearing (10) is inclined to the vertical at an angle somewhat greater than that of the bolt-lock bearing (14), so that the lock constitutes a wedge, the difference between these angles being sufficiently low 90 to prevent the wedge lock from being forced downwardly from between the bolt and receiver during high breech pressure but being sufficiently high to cause the lock to be forced down when the breech pressure has 95 decreased to a relatively low value, according to the disclosures in the aforesaid patent and applications. When the lock moves downwardly out of locked position, the legs 6 slide in the bolt grooves 2 and the central 100 portion shown in section in Figs. 1 and 8 slides downwardly into the recess 1 in the firing member. The downward movement of the lock is limited either by the lower ends of the legs engaging against the bottom of the receiver or by the central portion 105 engaging the bottom of the recess in the firing member. As the lock moves downwardly the firing member is retracted relatively to the bolt and the bolt is retracted 110 relatively to the receiver due to the obliquity of the abutting surfaces between the parts. After the lock has moved downwardly sufficiently to clear the bearing plate 19 the bolt and lock and firing members 115 move rearwardly as a unit, the surface 11 of the lock sliding along the upper surface of the receiver chamber. When the recoil spring returns the unit forwardly the inclined shoulders 9 on the lock engage the 120 similarly inclined shoulders 28 and 29 on the receiver to cam the lock upwardly into locked position. The recoil spring bears only against the rear end of the firing member so that its force is transmitted to the 125 bolt through the medium of the lock; and owing to the reverse obliquity of the engaging surfaces between the firing member and lock, the firing member also applies an upward component of force to the lock. The 130

reverse obliquity of the abutting surfaces between the firing member and lock is much less than the obliquity of the abutting surfaces between the lock and bolt so that the 5 firing member is advanced relatively to the bolt during the final closing and locking movement of the bolt, firing the cartridge at the end of the forward stroke.

From the foregoing it will be evident that 10 the breech pressure is transmitted to the receiver through the transverse body portion 7 of the lock and that this portion of the lock is subjected to compression only, there being no shearing or other stresses, the lock abutting faces of the bolt and receiver being substantially opposite along a line inclined to the line of breech pressure. Moreover, the lock bears on the receiver throughout its entire width along a flat surface of large area; 15 and at the same time the vertical movement of the lock in locking or unlocking is very short. Furthermore, the body of the lock bears against the bolt (surface 14) throughout the width of the lock except at the central slot 16. And the difference in bearing area between the surfaces 10 and 14 due to the slot 16 may be made sufficient to compensate for the greater pressure on surface 10 due to its greater obliquity so that the 20 pressure on the opposite sides of the lock may be made substantially equal per unit area. In order properly to distribute the pressure over the surfaces 10 and 14 of the lock, these surfaces should be symmetrical 25 with respect to a plane through the center of the body 7 perpendicular to the bisector of the angle between the surfaces. Thus in the illustration the surfaces 10 and 14 are symmetrical with respect to a plane $x-x$ (Fig. 30 9) which intersects a plane $y-y$ (which makes equal angles with surfaces 10 and 14 or bisects the angle therebetween) along a line z which in turn is parallel to the plane of the upper surface of the breech block.

45 I claim:

1. A gun having a firing chamber and a bolt chamber, a bolt movable in the bolt chamber along a straight path substantially parallel with the axis of the firing chamber, 50 the bolt and bolt chamber having opposed recesses extending substantially across one side of the bolt, and a lock movable between a position in the recesses where it engages the bolt recess along its forward side and 55 the chamber recess along its rearward side, in which position it locks the bolt closed, and a position substantially within one recess, in which position the bolt is free to be retracted along said path, the lock abutting 60 faces of the bolt and receiver being substantially opposite along a line inclined to the line of breech pressure.

2. A gun having a firing chamber and a bolt chamber, a bolt movable in the bolt 65 chamber along a straight path substantially

parallel with the axis of the firing chamber, the bolt and bolt chamber having opposed recesses extending substantially across one side of the bolt, and a lock movable between a position in the recesses where it engages the bolt recess along its forward side and 70 the chamber recess along its rearward side, in which position it locks the bolt closed, and a position substantially within one recess, in which position the bolt is free to be 75 retracted along said path, the lock abutting faces of the bolt and receiver being substantially opposite, and the engaging surfaces between said lock and recesses being inclined to the line of breech pressure at such 80 angles as automatically to unlock the bolt in response to the breech pressure acting thereon.

3. A gun comprising a receiver, a bolt reciprocatable in the receiver, the receiver and bolt having opposed recesses extending transversely thereof, a bolt lock having a polygonal body disposed transversely of the bolt and receiver, said body being adapted to abut against the faces of the bolt and receiver recesses respectively along surfaces substantially opposite to each other throughout substantially their entire abutting areas and to move substantially wholly into one of the recesses to permit the bolt to retract. 95

4. A gun comprising a receiver, a bolt reciprocatable in the receiver, the receiver and bolt having opposed recesses extending transversely thereof, a bolt lock having a polygonal body disposed transversely of the bolt and receiver, said body being adapted to abut against the faces of the bolt and receiver recesses respectively along surfaces substantially opposite to each other and to move substantially wholly into one of the recesses to permit the bolt to retract and the engaging surfaces between said lock and recesses being inclined to the line of breech pressure at such angles as automatically to unlock the bolt in response to the breech 105 pressure acting thereon.

5. A gun comprising a receiver, a bolt reciprocatable in the receiver, the receiver and bolt having opposed recesses extending transversely thereof, a bolt lock having a polygonal body disposed transversely of the bolt and receiver, said body being adapted to abut against the faces of the bolt and receiver recesses respectively along surfaces substantially opposite to each other and to move substantially wholly into the bolt recess to permit the bolt to retract, and said lock having a leg slidable in a guideway in the outside of the bolt. 115

6. A gun comprising a receiver, a bolt reciprocatable in the receiver, the receiver and bolt having opposed recesses extending transversely thereof, a bolt lock having a polygonal body disposed transversely of the bolt and receiver, said body being adapted 125 to abut against the faces of the bolt and receiver recesses respectively along surfaces substantially opposite to each other and to move substantially wholly into the bolt recess to permit the bolt to retract, and said lock having a leg slidable in a guideway in the outside of the bolt. 130

to abut against the faces of the bolt and receiver recesses respectively along surfaces substantially opposite to each other and to move substantially wholly into the bolt recess to permit the bolt to retract, and said lock having legs slideable in grooves in opposite outer sides of the bolt respectively.

7. A gun comprising a receiver, a bolt reciprocatable in the receiver, the receiver and bolt having opposed recesses extending transversely thereof, a bolt lock having a polygonal body disposed transversely of the bolt and receiver, said body being adapted to abut against the faces of the bolt and receiver recesses respectively along surfaces substantially opposite to each other throughout substantially their entire abutting areas and to permit the bolt to retract, said lock being confined substantially to the transverse dimension of the bolt.

8. A gun comprising a receiver and a breech bolt having opposed bearing surfaces inclined to the line of breech pressure, said surfaces being respectively disposed substantially wholly on opposite sides of a plane parallel to said line, and being substantially symmetrical with respect to a plane which intersects, along a line parallel with said plane, a plane making equal angles with said surfaces, and a breech lock intercalated between said surfaces to lock the bolt closed, said lock being movable to one side of said plane to unlock the bolt.

9. A gun comprising a receiver and a breech bolt having opposed bearing surfaces inclined to the line of breech pressure, said surfaces being respectively disposed substantially wholly on opposite sides of the plane of one side of the bolt and being substantially symmetrical with respect to a plane which intersects, along a line parallel with said plane, a plane making equal angles with said surfaces, and a breech lock intercalated between said surfaces to lock the bolt closed, said lock being movable to one side of said plane to unlock the bolt.

10. A gun comprising a receiver, a breech bolt slideable in the receiver, one side of the

bolt being disposed in juxtaposition to one side of the receiver along a longitudinal plane, the receiver and bolt having opposed transverse recesses so inclined that the forward face of the bolt recess is disposed on one side of said plane and the rearward face of the receiver recess is disposed on the other side of said plane, and the two faces are substantially opposite to each other throughout substantially their entire operative areas, and a lock disposed between said faces to transmit the breech pressure to the receiver, said lock being movable to one side of said plane to unlock the bolt.

11. A gun comprising a receiver, a bolt slideable in the receiver, the bolt and receiver having opposed locking abutments, a bolt lock movable into and out of position between said abutments, the set of abutting surfaces between the lock and receiver abutment and the set of abutting surfaces between the lock and bolt abutment being inclined relatively to each other at such angles that the breech pressure tends to force the lock from between the abutments, and the lock being so intercalated between the abutments as to transmit the breech pressure from the bolt to the receiver essentially by compression.

12. A gun comprising a receiver, a bolt slideable in the receiver, the bolt and receiver having opposed locking abutments, a bolt lock movable into and out of position between said abutments, the set of abutting surfaces between the lock and receiver abutment and the set of abutting surfaces between the lock and bolt abutment being inclined relatively to each other at such angles that the breech pressure acting through the bolt forces the lock from between the abutments a predetermined interval after firing, and the lock being so intercalated between the abutments as to transmit the breech pressure from the bolt to the receiver essentially by compression.

Signed by me at Cleveland, Ohio, this 11th day of December, 1919.

OSCAR V. PAYNE.
